REFRIGERATION EQUIPMENT FOR BEER
COOLING AND ICE-CUBE MAKINGCarl John Schmock, Erie, Pa., assignor to The
Uniflow Manufacturing Company, Erie, Pa., a
corporation of Pennsylvania

Application February 7, 1951, Serial No. 209,743

4 Claims. (Cl. 62—2)

1

This invention relates to the art of refrigeration and is especially concerned with equipment adapted for use in the refrigeration of beverages, for instance beer to be served in bars, taprooms and the like.

In installations of the kind referred to above it is desirable to provide for the refrigeration of beverages in several different forms, for instance barreled beer and bottled or canned beer. It is also desirable to provide a supply of ice.

The present invention is concerned with refrigeration equipment particularly adapted to the above purposes and integrating the several functions in a novel manner.

More specifically, the system of the invention contemplates the use, in combination with a single compressor and condensing unit, of evaporator elements disposed in different kinds or sizes of compartments adapted for refrigeration of different kinds or sizes of beverage containers, provision being made for independent temperature control in the several chambers, notwithstanding operation of all of the evaporators from a single compressor and condensing unit.

In addition to the foregoing certain features of the invention are concerned with the structure and arrangement of a special chamber particularly adapted to the functions of chilling bottled or canned beverages and also for the production of ice cubes.

The manner in which the foregoing objects and advantages are attained will appear from the following description referring to the accompanying drawings illustrating the preferred embodiment of the invention.

Figure 1 is an elevational view of refrigeration equipment according to the present invention, the doors for the refrigerating chambers being removed to disclose the parts lying within; and

Figure 2 is an end view of the cabinet with the end wall removed.

Referring to the drawings a thermally insulated cabinet is generally indicated by the reference numeral 1. Attached to this cabinet is a second cabinet 2 enclosed in which is the refrigeration system compressor and condensing unit (not shown). While the compressor and condensing unit may be arranged remote from cabinet 2, as here is shown it is directly associated with the main cabinet 1. Since the details of this unit and its cabinet form no part of the present invention per se, they are shown only in outline herein. The insulated cabinet 1 is comprised essentially of two refrigerating chambers 3 and 4 which are separated within the cabinet

55

2

with a structure 5. The space comprising chambers 3 and 4 is surrounded on all sides by insulating material 6. The insulating material may be of any suitable type such as cork or glass wool and is held between the inner and outer shells of the cabinet. Chambers 3 and 4 are provided with insulated doors which are not shown.

The outer shell is indicated by the reference numerals 7 and 8 forming the side members and 10 and 10 forming the top and bottom respectively. The rear is indicated by reference numeral 11. The inner shell is generally indicated by the reference numerals 12 and 13 forming the sides and 14 and 15 forming the top and bottom. The rear 15 is indicated by reference numeral 16.

Chamber 3 is adapted to receive barrels of beer 17 and is further provided with an appropriate cooling system. The cooling system used in chamber 3 may be of any of the generally known types. Shown in Figure 1 is a blower type cooling unit comprising essentially evaporator 18 and air circulation fan 19. Refrigeration lines incident thereto are referred to hereinafter.

Chamber 4 is divided into upper compartment 20 and a lower compartment 21. The upper compartment 20 is adapted for the cooling of beverages and to this end is provided with shelving 22 and 22a for the storage of cans or bottles of beer. The lower compartment 21 has an evaporator unit 23 which is adapted for the making of ice cubes. Further, the lower compartment has a fan 24 which is utilized to circulate air through the lower and upper compartments. The direction of the airflow is shown by the arrows on Figure 2.

Mounted on top of cabinet 1 is a conventional beer dispensing unit 25 having dispensing taps 26 which are adapted to receive beer from the barrels 17 by means of beer delivery lines not shown.

Figure 2 illustrates in particular the compartments 20 and 21 which were briefly described above and these are now described in greater detail.

Mounted in compartment 21 is an evaporator unit 23. The evaporator is comprised of tubing 27 for the carrying of the refrigerant. The tubing is bent with a multiplicity of parallel runs adapted to support a plurality of horizontally extending covers or shelves 28. The shelving arrangement is adapted to receive containers for the freezing of water such as the ice cube trays 29. As will be understood, the common forms of cold plates may readily be employed instead of tubing such as indicated at 27.

Mounted adjacent the evaporator unit is an

electric fan 24. The fan may be of any conventional type but it is important that it be capable of operating under low temperature conditions.

Disposed above the fan is an air duct 30. Two sides of the air duct are defined by part of the inner shell 16 and the vertically extending structure 31. The other two sides being defined by part of the inner shell 12 and part of the structure 5. As clearly shown on Figure 2 the air duct provides communication for the passage of air from the lower compartment 21 to upper compartment 20; the air entering lower opening 32 and leaving upper opening 33. Circulation of air in the reverse direction could also be utilized.

Shelf 22 which is diagrammatically illustrated may be of any suitable construction so as to permit the downward passage of air, for example, it can be perforated or constructed with a plurality of crisscross wires. Lower shelf 22a divides compartments 20 and 21 and in addition is adapted to permit passage of air from upper compartment 20 to lower compartment 21.

It is important in the operation of the system that substantially all of the air passing through upper compartment 20 and thence to lower compartment 21 be drawn through at least a major portion of the evaporator unit 23. This direction of airflow is accomplished by the construction of shelf 22a. The shelf extends over the fan and the evaporator unit and is for the most part a solid member; however, the end portion 33a is adapted to permit passage of air. As shown in Figure 2 the end portion 33a is provided with perforations 34 in an area extending from edge 35 toward the center. The perforated area preferably extends substantially the full width of the shelf. Although I have shown in Figure 2 the end portion 33a to be provided with perforations 34 the same effect may be accomplished for example by shortening the length of the member.

Having described the construction of cabinet 1 and chambers 3 and 4 I wish to generally describe the refrigerating system. As mentioned heretofore the compressor and condensing units are enclosed in cabinet 2. The liquid line 36 running from the condenser is disposed near the top of the cabinet and runs to a T-joint 37. From the T-joint 37 part of the refrigerant then goes to a thermostatic expansion valve 38 for the evaporator unit 18 of chamber 3 and the other part goes to thermostatic expansion valve 39 for the evaporator 23 of lower compartment 21. The vaporized refrigerant from the evaporator unit 18 flows (under suction of the compressor unit) through constant pressure valve 40 and thence to the common T-joint 41. The vaporized refrigerant from the evaporator unit 23 runs directly from the evaporator via line 42 to common T-joint 41. The vaporized refrigerant then flows to the compressor unit through suction line 43.

The temperature of the chamber 3 is regulated by the cooling unit comprising evaporator 18 and fan 19. The temperature of the lower compartment 21 is regulated by the temperature of the evaporator 23.

The temperature of the evaporator 18 is controlled by the pressure setting of the constant pressure valve 40. The desired chamber 3 temperature (preferably 42° F.) may be set by nob 44 which influences the operation of the fan 19. The temperature of the evaporator unit 23 is controlled by the pressure setting on the condensing unit (not shown). An evaporator temperature of +5 to +15° F. is preferable. The details of these systems are not illustrated as they form no

part of the present invention, per se, and also are well understood by those skilled in the art. However it is noted that temperature control of evaporators 18 and 23 is gained by means of pressure control. This allows simplicity of control while obtaining two different evaporator temperature levels from a single compressor and condensing unit.

Temperature of the upper compartment 20 is regulated by the cold air flowing therethrough and the airflow depends upon operation of the fan. Although the fan may be operated continuously under variable speed control, I prefer intermittent operation and to this end the fan is thermostatically controlled. The thermostat can be of any of the generally known types. However the thermostat which I prefer comprises essentially a temperature sensitive bulb 45 controlling a relay which opens and closes the power circuit for fan 24. The bulb is mounted in upper compartment 20 and communicates by line 46 with a regulating relay located in casing 47 mounted in chamber 3. The regulating relay is connected with the fan as by line 48. The system is so arranged that when ambient temperature of the bulb rises above a certain value, the response of the bulb is communicated to the relay which closes the fan operating circuit. Cold air is then circulated in the compartment until such time as the temperature drops to the desired level. The desired temperature of the compartment may be set by means of nob 49. I prefer to hold the temperature at approximately 38° F.

The refrigerating system which I have described has particular advantage over the ordinary direct draw or other "under-the-bar" beer dispensing units. It is seen that in one cabinet are located a unit for draft beer, a unit for canned or bottled beer and a unit for ice cube making. All these facilities are in one limited space. For the small crowded tavern this is of considerable importance not only from the standpoint of saving space but also from the standpoint of saving in cost as the system I have described entails less expense than two or three separate refrigerating units.

I claim:

1. Refrigeration equipment comprising, in combination with a compressor unit and a relatively large refrigerating chamber adapted to receive barreled beverages and having an evaporator therein, a relatively small refrigerating chamber divided into upper and lower compartments with shelving for support of bottled beverages in the upper compartment, an evaporator in the lower compartment comprising a coil bent to provide a multiplicity of runs positioned to define shelving for supporting containers for the freezing of water, this last shelving serving also to define at least one boundary of a horizontally extending air circulation passage; partition structure extending upwardly from one end of said passage to define an upright air circulation duct the upper end of which is open to the upper portion of the upper compartment, a lower portion of the upper compartment being in communication with the other end of said horizontal passage, an air circulation fan adjacent one end of said passage for circulating air through said passage in contact with said evaporator coil and thence upwardly through said duct and into the upper portion of the upper compartment to be returned to the said passage; the evaporators in the large and small refrigerating chambers both being connected with said compressor unit, and

independently operating temperature controlling systems for the large and small chambers including for the small chamber a temperature responsive device in this chamber located in the upper compartment thereof and connected to regulate the operation of the air circulation fan.

2. Refrigeration equipment comprising: a compressor unit; a relatively large refrigerating chamber adapted to receive barreled beverages; an evaporator unit in said chamber connected with said compressor unit; a fan for circulating air in said chamber; control means to regulate the operation of said fan whereby to control the temperature in said first chamber; a second refrigerating chamber smaller than said first chamber and divided into upper and lower compartments with shelving for support of articles in the upper compartment, the lower compartment being smaller than the upper compartment; partition structure separating said chambers; a second evaporator in said lower compartment connected with said compressor unit and comprising a coil bent to provide a multiplicity of runs positioned to define shelving for supporting containers for the freezing of water, this last shelving serving also to define one boundary of a horizontally extending air circulation passage; baffle structure extending upwardly from one end of said passage to define an upright air circulation duct, the upper end of which is open to the upper portion of said upper compartment; a horizontally extending member dividing said compartments, one end of which engages said baffle structure, the other end being adapted to define an air circulation port between the lower portion of the upper compartment and the other end of said horizontal passage; an air circulation fan adjacent the lower end of said duct for circulating air through said horizontal passage in contact with said evaporator coil and thence upwardly through said duct and into the upper portion of the upper compartment to be returned to the lower compartment through said port; and second control means having a temperature responsive element in said upper compartment to regulate the operation of said fan where-

by to control the temperature in the compartment.

3. Refrigeration equipment comprising: a refrigerating chamber divided into upper and lower compartments with shelving for support of articles in the upper compartment; an evaporator in the lower compartment comprising a coil bent to provide a multiplicity of runs positioned to define shelving for supporting containers for the freezing of water, this last shelving serving also to define one boundary of a horizontally extending air circulation passage; partition structure extending upwardly from one end of said passage to define an upright air circulation duct the upper end of which is open to the upper portion of the upper compartment; a horizontally extending member dividing said compartments, one end of which engages said partition structure, the other end being adapted to define an air circulation port between the lower portion of the upper compartment and the other end of said horizontal passage; and an air circulation fan adjacent the lower end of said duct for circulating air through said passage in contact with said evaporator coil and thence upwardly through said duct and into the upper portion of the upper compartment to be returned to the lower compartment through said port.

4. A construction in accordance with claim 3 further including means to maintain the evaporator in said lower compartment at a temperature between +5 and +15° F. and control means in said upper compartment to regulate the operation of said air circulation fan whereby to maintain the temperature in the upper compartment at approximately 38° F.
